UNITED STATES PATENT OFFICE.

ALBERT F. PRESTON, OF LYNN, MASSACHUSETTS.

MACHINE FOR MARKING VAMPS FOR BOOTS OR SHOES.

SPECIFICATION forming part of Letters Patent No. 360,325, dated March 29, 1887.

Application filed January 10, 1887. Serial No. 223,918. (No model.)

To all whom it may concern:

Be it known that I, ALBERT F. PRESTON, of Lynn, in the county of Essex and State of Massachusetts, have invented certain new and useful Improvements in Vamp - Marking Machines for Boots or Shoes, of which the following is a full, clear, and exact description.

This invention consists of an apparatus suitably constructed and arranged to mark and indicate on a vamp for a boot or shoe the places where to stitch on the quarters and the toe-tips, and the center line of the vamp for the proper location of the quarter-seam, all at one operation, all substantially as hereinafter fully described, reference being had to the accompanying plate of drawings, in which—

Figure 1 is a plan view. Fig. 2 is a side view. Fig. 3 is a plan view below line 3 3, Fig. 2; and Fig. 4 is a plan view of the under side of the working parts of the apparatus; Fig. 5, a partial side view and partial vertical sectional view on line 5 5, Fig. 1; Fig. 6, a plan view of a vamp, as marked by the present apparatus. Fig. 7 is a detail cross-section on line 7 7, Fig. 1. Fig. 8 is a detail cross-section on line 8 8, Fig. 3; Fig. 9, a detail plan view. Fig. 10 is a detail plan and partial sectional view, and Fig. 11 is a detail sectional view.

In the drawings, A represents a table or bed, to which is hinged the bar B, at a, for it to swing up on such hinge, as shown, for instance, in Fig. 2 in side view.

C is a transverse rib or bar secured to the bed-plate A, and having at each end a block, D, secured to the bed A, through which extends the right and left hand screw E, arranged to freely turn in said blocks, but prevented from moving longitudinally by shoulders b, and a central block, F, secured to the plate, and having a milled middle head, d, for operation thereof.

G H are two arms, each having a transverse groove, e, on its under side, fitting over the rib G, one, H, on the right-hand screw portion, J, and the other, G, on the left-hand screw portion, K, of the screw E, and each having a corresponding screw-thread to engage with its respective screw, their ends f projecting toward the front end of the bed-plate and resting thereon.

Turning the screw E by its head to the right

or left correspondingly moves the arms G H toward or from each other, the distance from each other being limited by the blocks D, the arms being arranged to slide freely along the rib C and over the plate A.

L M are two arms between the guide-arms G H, each screwing on to its respective screw K J, and by the turning of which they will move toward and from each other, and with the movements of the guide-arms, each being screwed onto its screw, so as to be close to its respective guide-arm, as shown in Figs. 1 and 3 in plan view.

The rear end, g, of each arm L M extends back, as shown in the drawings, and bends upward slightly, so that each arm can swing vertically on its screw as a pivot, a certain distance for the end h to be, when in its normal position, away from or above the bed-plate, a short distance, as shown in side view in Fig. 2 more particularly.

The bar B has a central cross-bar, N, rigidly secured to it, extending each side thereof, and is so located on the bar that when the bar is swung down upon the plate the cross-bar will by its ends strike on the upper side of the ends h of the arms L M, and press such ends down upon the table, the arms swinging on their respective screws as pivots, and when the bar is swung up the arms will return to their positions (shown in Fig. 2) from the weight of the outer ends, g, of such arms.

P is a cross-arm on the under side of the bar B, and fitting over the same by a transverse groove on its upper side, and in such manner that it can freely move back and forth along such bar.

Q is a screw freely turning in blocks R R on the bar B, but prevented from longitudinal movement along the bar, the screw passing through the cross-bar P, its screw-thread engaging with a screw-thread in the cross-bar P, so that turning the screw Q to the right will move said cross-bar toward the end a of the bar, and to the left said bar in the reverse direction.

S is another screw parallel to the screw Q, adapted to freely turn in the blocks R, but so as not to move longitudinally therein, and passing through, engaging by its screw-thread with a screw-thread in a block, T, arranged to

slide on the under side of the bar B. Turning the screw S to the right will cause the block T to move toward the outer end of the bar B, and to the left in the reverse direction.

5 The screw Q passes through an opening, n , in this block T, but allows it to move freely thereon.

Pivoted to and on the under side of the bar B at q is a flat strip, U, which by one end is 10 pivoted at r to the end of another strip or bar, V, pivoted by its end to a block, W, adapted to slide back and forth in a longitudinal groove, t , in the bar B, having a thumb-screw, a , on the upper side of the bar B, screwing into 15 the block W, and arranged to secure said block firmly at any point along said groove.

The strip or bar U extends to and beyond the cross-arm P, and is arranged to lie and 20 freely slide laterally within a horizontal groove, v , in the portion w of the cross-arm. The center of the pivot q on which this strip turns is 25 in the same vertical plane as the front edge, y , of the transverse rib C. (See Fig. 11.)

On the strip U at z is marked a scale representing the different sizes of boots and shoes 25 according to their lengths, from 5's children's boots or shoes at a' to 12's men's boots and shoes at b' , and in the strip is a scale of holes, d' , which are arranged on the strip in line 30 with and from the pivot q , and are marked by the letters of the alphabet, as shown.

On the under side of the end h of each arm L M is a narrow rib, e' , extending across the face, as shown in Fig. 10 more particularly, 35 and on the under side of the block T is a cross-rib, f' , and another rib, g' , crossing it, as shown in Fig. 9. The cross-arm P is cut away, as shown in Figs. 2 and 5, more particularly at h' , making a thin under edge at its front side, 40 as shown in said figures. These several ribs $e' f' g'$ and edges h' are sufficiently thin that, if pressed firmly upon a piece of leather or a similar material, they will leave corresponding indentations or impressions, but are not sharp 45 enough to cut or mar the surface of the leather.

The operation of the apparatus is substantially as follows: First, cut the vamp Y, which is shown in plan view in Figs. 1, 3, and 6, to the size and shape desired in any of the usual 50 ways, and having raised the bar B into the position shown in Fig. 2, lay the vamp on the table, its two ends, l' , against the front side, y , of the cross-rib C and between the two guide-arms G H, and then turn the screw E 55 until such arms touch the ends l' , as shown in plan view in Fig. 3. Then set the thumb-screw block W along the groove t until its mark m' coincides with the mark on the scale z , indicating the length of the boot or shoe for 60 which the vamp is intended, which in the present case, say, is No. 5 of men's sizes, and fasten the thumb-screw at such place to prevent the block W moving, and then move the cross-bar P by its screw Q along the bar B until its edge h' is over the place on the vamp where it is desired to place and secure the toe-tip. Now swing or let down the arm B and

press the same firmly upon the vamp placed, as described, upon the table. When raising the arm, the vamp will be found marked, as 70 shown in Fig. 6 at r' , by the arm-edges h' of the bar P, showing where the toe-tip is to be attached, its edges being placed to such marks; at s' the center of the vamp, and at t' by the ribs on the arms L M and block T, where the quarters 75 are to be attached to the vamp. Having thus marked one vamp, other vamps of the same size on which it is desired to locate the toe-tips in the same position can be marked in the same manner, and all will be marked exactly 80 alike.

Making a memorandum of the hole d at the edge h of the cross-bar P in the strip U by its number, the apparatus can be set at any time for the marking of other vamps the same. 85

To change the apparatus to mark another size of boot or shoe vamp, and keep the relative proportions of the toe-tip mark to its length, unloosen the thumb-screw w and move the block W along its groove t until its mark m' is opposite the desired size indicated on the scale z , and then cause the cross-bar P to move along the bar B by its screw until its front edge, h' , is over and coincides with the same hole, as indicated by the letter that was used 90 for the first vamp marked, and then the vamp, when placed in the apparatus, and the guide-arms moved, as described, to suit its width, if necessary, will be marked for its toe-tip to be 95 in the same relative position on the vamp for its size as compared with the first one. When the bar is raised the marking-ends h of the arms L M are raised, from the plate by the weight of their rear ends, g , leaving the bed-plate free to place a vamp under them and 100 against the rib in position to be marked. 105

In lieu of the arms L M returning to their normal position by gravity, as described, they can be operated by springs, &c., or in any suitable manner. 110

The marking-rib g' on the under side of the block T is arranged the proper distance from the front edge or side u' of the block for the marking of the quarter-seam, and the block is set by its screw for its front edge to be in line with the line v' of the vamp, and its marking-rib f' is arranged to be centrally between the guide-arms G H; also, the marking-ribs e' on the under side of the arms L M, are arranged the proper distance from the front edge, y , of 115 the rib for their proper marking. 120

The pivot of the strip U on the bar B and its connection with the thumb-screw block is so arranged that the distance between the pivot q and its pivot on the block W represents the 125 length of a boot or shoe, and the distance from the pivot q to the front edge, h' , of the cross-bar P represents the length from the edge of the tip to the back edge of the vamp, so that when the cross-bar P is adjusted to the same 130 letter on the strip U the relative proportions of these two distances will be the same for all sizes.

This apparatus can be made of any suitable

material, although if the bed-plate is made of wood or similar material it can have a plate, Z, of metal secured on its upper side, as shown in the drawings, for a better surface on which 5 to operate.

Any suitable marking devices can be used other than the ribs shown.

If desired, a spring can be arranged between the bed-plate and the bar B in such manner 10 that it will hold the bar up in the position shown in Fig. 2 for the convenient insertion of a vamp to be marked and to return it automatically to such position after a vamp has been marked.

15 The block W can be arranged to move back and forth on the bar B in other ways than sliding in a groove.

Having thus described my invention, what I claim is—

20 * 1. In a vamp-marking machine, the combination, with a bed-plate, A, having pivoted thereto a bar, B, with a groove, t, and a scale, z, of a strip, U, having a scale, d, and pivoted to said bar and connected to a block, W, adapted 25 to slide along said groove, and an adjustable bar, P, for the purpose specified.

2. The combination, with a bar, B, provided with a groove, t, and a scale, z, of a strip, U, having a scale, d, and pivoted to said bar and 30 connected by a bar or arm, V, to a block, W, adapted to slide along said groove and be secured therein, for the purpose specified.

3. The combination, with a guide-bar, C, of a right and left hand screw, E, and two arms, L 35 M, engaging, respectively, the portions K J of said screw, and each provided with a marking device, e², and operated by a bar, B, for the purpose specified.

4. The combination, with a bar, B, of a block, T, provided with a marking device and arranged to slide along thereon and operated by means of a screw, S, for the purpose specified. 40

5. The combination, with a guide-bar, C, of a right and left hand screw, E, suitably attached to blocks D for turning therein, and two arms, 45 L M, engaging, respectively, the portions K J of said screw and each provided with a marking device, e², for the purpose specified.

6. The combination, with a guide-bar, C, and a right and left hand screw, E, engaging with 50 the guide-arms G H, of two arms L M, each provided with marking device and engaging with said screws and adapted to slide along said bar, for the purpose specified.

7. In a vamp-marking machine, the combination, with a bed-plate having pivoted thereto a bar, B, provided with a scale, Z, of a strip, U, having a scale, d, and pivoted to said bar and connected to a block, W, adapted to move back and forth on said bar and to be secured 60 thereto, for the purpose specified.

8. The combination, with a bar, B, of a block, T, adapted to move back and forth on said bar and provided with marking devices f² and g² for marking the center of the seam and place 65 for the attachment of the quarter to the vamp.

In testimony whereof I have hereunto set my hand in the presence of two subscribing witnesses.

ALBERT F. PRESTON.
